(57) **CLAIM**

The ornamental design for a fabric sweeper, as shown and described.

DESCRIPTION

This design application claims priority to U.S. Ser. No. 11/450,315, filed Jun. 10, 2006, currently pending and entitled "Fabric Sweeper" which is herein expressly incorporated by reference in its entirety, for all purposes.

FIG. 1 is an isometric view of a fabric sweeper, embodying a new design; and,

FIG. 2 is a bottom plan view of the fabric sweeper of FIG. 1. The broken lines shown in the drawings are for illustrative purposes only and form no part of the claimed design. The fabric sweeper is symmetric such that the front and back are identical, and the opposing sides are identical as well.
